UNITED STATES PATENT OFFICE.

JAMES C. GEORGE AND GABRIEL L. GEORGE, OF BRISTOL, VIRGINIA.

GRATE.

1,278,135.

Specification of Letters Patent. Patented Sept. 10, 1918.

Application filed May 24, 1917. Serial No. 170,751.

To all whom it may concern:

Be it known that we, JAMES C. GEORGE and GABRIEL L. GEORGE, citizens of the United States, residing at Bristol, in the 5 county of Washington, State of Virginia, have invented a new and useful Improvement in Grates, of which the following is a specification.

The present invention appertains to grates 10 for the fire boxes of locomotives, furnaces, and the like, and is particularly an improvement over the furnace grate disclosed in our Patent 1,220,216, March 27, 1917.

It is the object of the invention to provide 15 grate bars the trunnions of which are mounted in a novel manner, bearings of special form being provided therefor whereby an improved construction of grate is obtained.

20 With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

25 The invention is illustrated in the accompanying drawing, wherein:—

Figure 1 is a fragmental plan view illustrating one grate bar and fragmental portions of the bearings.

30 Fig. 2 is a section on the line 2—2 of Fig. 1.

Fig. 3 is a cross section of the grate bar, taken on the line 3—3 of Fig. 2.

35 Fig. 4 is a fragmental elevation of one of the grate bars showing the manner of assembling one end of the frame and hanger.

Fig. 5 is an elevation of one of the bearings, a portion thereof being shown in section.

40 Only one of the grate bars is shown and described, since they are duplicates of one another, being disposed side by side. The grate bar is provided at each end with an upwardly extending end plate constituting a hanger. Each hanger is provided with an

45 outstanding trunnion 2 near its upper end for engaging a support. An inwardly extending hook shaped seat 3 extends from the lower end of the hanger, the free end portion of the seat being extended upwardly. Said seat has a shoulder 4 adjacent its free

end portion and a recess 5 is provided between this shoulder 4 and the body portion of the hanger. An inwardly extending lug 6 projects from the hanger directly opposite the trunnion 2, this lug overhanging the seat 3 and being spaced thereabove.

Supported between the two hangers is an elongated open frame or saddle 7, which can be cast from suitable metal the same as the hangers 1, although the parts can be otherwise manufactured. The ends of the frame 7 abut the hangers and seat on the shoulders 4, the lugs 6 of the hangers overhanging the end portions of the frame 7, whereby to hold said frame on the seats 3, and prevent the accidental jumping of the frame from its seats, thus holding said parts assembled. The ends of the frame 7 are beveled, as at 8, at their lower portions, and 50 their upper portions are rounded, as at 9, whereby to facilitate the assemblage of the parts. Thus, referring to Fig. 4, when the hangers are disposed in an inclined position with the hook-shaped seats 3 engaged under the ends of the frame 7, the beveled or cut away portions 8 will accommodate the hangers, and then as the hangers are swung to upright position in the direction of the arrow in Fig. 4, the lugs 6 can move over the 55 curved portions 9 onto the end of the frame, the shoulders 4 moving into engagement with the ends of said frame, whereby to properly assemble the parts, with the lugs 6 holding the ends of the frame to its seat in 60 abutment with the hangers. To detach the parts, the hangers must be swung away from one another to remove the lugs over the ends of the frame, and since this is not possible when the hangers are held by the bearings, 65 the parts cannot separate accidentally.

The frame 7 supports a series or row of grate sections 10 of suitable construction and preferably cast. Each of the sections 10 has a pair of flat depending shanks or 70 standards 11, which are provided with shoulders 12 seatable upon the upper edges of the side members of the frame 7, while the lower portions of the shanks 11 fit between said side members. The shanks 11 are provided 75 at their side edges with notches 13 adjacent to the shoulders 12, and the side members of the frame 7 are provided at suitable intervals or spaced points with inwardly extending lugs 14 to enter said notches when the 80 sections 10 are in normal position. To apply the sections 10, their shanks 11 are inserted 85

downwardly within the frame at the ends of the lugs 14, and when said sections are shifted longitudinally into proper position, notches 13 will engage the lugs 14. Said 5 notches provide hooks movable under the lugs or flanges 14, for holding the sections 10 seated on the frame 9, whereby said sections cannot jump out or fall from the frame 7, during its oscillation.

10 In assembling the parts the sections 10 are first applied to the frame 7, and the hangers 1 are then applied to the frame, and when swung into place, will shift and hold the sections 10 therebetween, the shanks 11 15 of the sections engaging the lugs 14. The hangers 1 will hold the sections 10 in proper position therebetween, and not until the hangers 1 are removed, can the sections 10 be slid longitudinally out of engagement with 20 the lugs 14 for removing said sections. When the hangers are detached from the bearings, however, they can be readily detached from the frame 7, and the sections 10 then separated, in order that any broken 25 or burnt out parts can be replaced.

Each of the frames 7 has a depending arm 15 for connection with a shaking device, for rocking the grate bars.

Each set or tier of grate bars is supported 30 transversely between a pair of parallel ledge bearings 16, which are provided with seats 17 in their upper edges for the trunnions 2. An elongated cap 18 is provided for each bearing 16, being disposed thereabove and 35 provided with recesses 19 for accommodating the trunnions 2 and permitting of a slight longitudinal movement of said cap. The cap is provided with a suitable number of depending hooks 20 movable downwardly 40 into recesses 21 with which the bearing is provided, and then by shifting the cap 18 longitudinally, the hooks thereof engage extensions 22 of the recesses, whereby to lock

the cap 18 on the bearing, and prevent its accidental detachment. A pin 23 is inserted 45 downwardly through the cap into the bearing 16, for preventing the cap 18 shifting longitudinally so that the hooks 20 can be removed, but by withdrawing the pin 23, the cap 18 can be readily detached, for the 50 removal of the grate bars.

When there are two tiers of grate bars, disposed side by side, as in wide locomotive grates, the intermediate bearing 16 is made sufficiently wide to accommodate the adjacent trunnions of the two sets of grate bars, 55 as will be readily understood.

Having thus described the invention, what is claimed as new is:—

1. A grate embodying grate bars having 60 trunnions, bearings having seats for said trunnions, a cap on said bearings to hold the trunnions in said seats, said caps and bearings having means interengageable when said caps are shifted longitudinally, and 65 means for preventing longitudinal movement of said cap.

2. A grate embodying grate bars having trunnions, bearings having seats for said trunnions, a cap seatable on said bearings to 70 hold the trunnions in said seats, said caps having depending hooks, the bearings having recesses for receiving said hooks and for preventing their withdrawal when the caps are moved longitudinally in one direction, 75 and a pin engageable with each of said caps and bearings for holding the hooks in engagement with the bearings.

In testimony that we claim the foregoing as our own, we have hereto affixed our signatures in the presence of two witnesses.

JAMES C. GEORGE.
GABRIEL L. GEORGE.
